UNITED STATES PATENT OFFICE.

EDWARD L. MCCLAIN, OF GREENFIELD, OHIO.

HORSE-COLLAR PAD.

SPECIFICATION forming part of Letters Patent No. 321,622, dated July 7, 1885.

Application filed July 9, 1884. (No model.)

To all whom it may concern:

Be it known that I, EDWARD L. MCCLAIN, a citizen of the United States, and a resident of Greenfield, in the county of Highland and State of Ohio, have invented a new and useful 5 Horse-Collar Pad, of which the following is a specification.

My invention relates to a device for adjustably attaching a pad to a horse-collar.

10 The object of my invention is to provide a means for securing a flexible piece, which is attached to the pad and is lapped around the fore roll of the collar and placed under the hame, for the purpose of adjustably attaching 15 a pad to a collar whereby the said flexible piece may be readily adjusted, and when adjusted may remain secured, and whereby the slack in the flexible piece may be automatically taken up in the operation of fastening the 20 hame to the collar.

Figure 1 shows in cross-section a horse-collar in place upon a collar-pad, and the flexible piece and attachment for securing the pad to the collar, and also the hame. Fig. 2 shows an edge view of the improvement, and Fig. 3 a top or side view of the same.

The same letters or numbers designate the same parts in all of the figures.

25 *a* is the fore roll, and *b* the back roll or body of the collar. *c* is the fore roll, *d* the back roll, and *E* the body of the pad.

There is no limitation to the kind of pad with which my improved fastening device may be used.

30 The flexible piece 1, which laps around the fore roll of the collar, may be of any suitable flexible material, as the material of which the pad-body is made, or leather, and it may be attached to the pad in any suitable manner, 35 as by sewing or riveting, and at any convenient suitable place, as to the upper side of the fore roll of the pad, or at or near the juncture 2 of the roll with the body of the pad.

The device which serves to draw the flexible piece 1 taut and snug against the fore roll of the collar and to secure the same when the hame is in place, is shown at 3. It is a binding-spring, consisting of a piece of flat elastic metal having two curved or projecting portions, *r* and *s*, uniting at an intervening angle

or short curve, *v*, and adapted to be suitably attached to the flexible piece 1, as by sewing or by means of rivets, as at 4. The flexible piece 1 may be fastened to the front part, *r*, only of the binding spring 3; or it may be extended under the whole length of the spring, and may be attached thereto by the rivets 5 also; or it may extend beyond the spring into a projection, 6, which may serve the fingers as a means of conveniently gripping the device 60 in attaching or adjusting it.

The curvature *r v s* of the binding spring 3 is made to correspond in position to the underlying curvature of the cross section of the collar at the place of attachment, but the said curvatures are not so great as the corresponding curvatures of the collar, so that when the spring 3 is merely laid in place upon the collar it does not fit down upon the latter and into the depression at the juncture of the roll *a* 70 with the body *b*, but rests thereon, as shown in Fig. 1. Now, when the hame 7 is drawn into the said depression in being fastened to the collar, it moves inward, as indicated by the arrow 8, and presses the center *v* of the 75 spring 3 down into the depression and snug against the collar. This bending of the spring 3 of course causes the curved portions *r* and *s* to draw into the depression, and, consequently, the flexible piece 1, to which the part *r* is attached, is drawn snugly upon and around the fore roll, *a*, of the collar, and hence secures the pad firmly to the collar. The curves *r* and *s* of the spring 3, by being bound upon and against the roll *a* and the body *b* of the collar 85 by the hame 7, are prevented from being displaced so long as the hame 7 remains secured to the collar. As soon as the hame is disengaged from the collar, the elasticity of the spring 3 causes it to spring away from its constrained position, and hence to automatically disengage the pad from the collar the instant the hame is loosened therefrom.

In attaching a pad provided with this fastening device to a collar, the pad may be first placed upon the horse's neck and then the collar placed upon the pad; or the pad may be placed within the collar and both put on the horse's neck at the same time.

When the hames are to be attached, the 100

springs 3 or the hand-pieces 6 are taken in the fingers and the flexible pieces 3 are drawn around the fore rolls, *a*, of the collar and the hames are pressed against the springs and 5 into the depressions *v*, and are then firmly secured to the collar.

The metallic portion 3 of the fastening device (illustrated in the figures) may be made of elastic wire bent into curves or angles like those *r v s* in the figures, and outside of these essential features may have any other shape or curves or arrangements which an artizan may desire to give it for the purpose of attaching it and adapting it to purposes herein set 15 forth.

The piece 1, or another piece, 6, attached to the binding-spring 3, may be made long enough to reach around the back roll, *b*, of the collar and be buckled or hooked to the back 20 part of the pad, or to a strap or piece attached thereto, as at the positions 11 or 12, and as

indicated by the dotted lines 10. When the hame is fastened to the collar, it will press the metal piece 3 into the depression beneath the hame and tighten the flexible portions which 25 lap around the collar-rolls, the same as above.

I claim—

The combination, with a collar-pad, of the flexible binding-strip 1, the elastic metallic binding-spring 3, having curved portions *r, v, s*, 30 and adapting it to the exterior contour of the collar and to be pressed into the depression at the juncture of the fore roll with the body of the same, and to be clamped between the hame and the collar, whereby it is made to tighten 35 the binding-strip to which it is attached to the collar, and hence to firmly secure the pad to the collar.

EDWARD L. McCALAIN.
